2,035,847

NECKTIE AND RETAINER THEREFOR

Alfred J. Strauss and John E. Huhn,
Louisville, Ky.Substitute for application Serial No. 618,031, June
18, 1932. This application September 7, 1935,
Serial No. 39,632

1 Claim. (Cl. 2-153)

This invention relates to masculine wearing apparel and has more specific reference to a made-up neck tie, either of the four-in-hand type or the bow type, and unique complementary retaining means for said necktie.

By way of introduction and in order that a clear understanding of the invention and its history may be comprehended, we deem it important, if not advisable, to mention at the outset that the subject matter of this application is identical with corresponding subject matter disclosed and claimed in a now abandoned but allowed divisional application filed by us under date of June 18, 1932 and identified as Serial No. 618,031, the present application being a substitute therefor.

Briefly described the invention herein covered, as well as that disclosed in the previous application, comprises a combination structure embodying a made-up necktie of the four-in-hand type including a knot, aprons, positioning tabs carried by the knot and adapted for disposition between the inner and outer folds of a conventional collar, and an adaptor element stitched to the back of the knot, and an ornamental retaining clip attached to said adaptor element, said clip serving to retain the tie on the collar as well as to hold the folds of the collar in symmetrical and neat position.

It goes without saying that our primary aim is to provide an assemblage of this specific classification which is characterized by simplicity and economy, durability from a standpoint of wear, and of such adaptation and special arrangement as to allow the ornamental clip to serve as a stay device for the folds of the collar as well as the sole means for supporting the made-up tie in operative association with said collar.

It is a matter of common knowledge that made-up ties, four-in-hand and bow type are in extensive use and that ornamental clips and clasps are independently used to promote a distinguished and well groomed appearance for the wearer and it is therefore our aim to combine the two factors in such a way that they form collectively an ingenious adaptation characterized by compactness and convenience so as to permit the two articles to be sold satisfactorily as a single unit.

Other features and advantages may become more readily apparent from the following description and drawing.

In the accompanying illustrative drawing wherein like numerals are employed to designate like parts throughout the same:

Figure 1 is a front elevational view showing the unique combination assemblage comprising the necktie and collar clip constructed in accordance with the principles of our invention and illustrating how the tie is worn.

Figure 2 is a rear elevational view showing more in particular how the special collar stay unit or clip is stitched on the knot of the tie.

Figure 3 is a perspective showing of the clip per se.

Referring now to the drawing by distinguishing reference characters it will be observed in Figure 1 that the numeral 7 designates the conventional collar either of the soft or so-called rigid type having the customary down-turned folds 8. The necktie, which is of the made-up four-in-hand type, is denoted by the numeral 9 and includes the usual companion aprons 11 and 12 coordinated with the standardized knot 10 and the outstanding positioning and stabilizing tabs 13.

The ornamental combination collar and tie clasp or clip is indicated as a unit by the numeral 14. This comprises a comparatively straight rigid bar 15 whose end portions terminate in 25 inturned hook-like curls to function as spring collar grips. The complementary bar is of a length slightly greater than the first-named rigid bar 15 and has its central curved portion disposed in contact with the intermediate part of the rigid 30 bar with its end portions 16 flaring outwardly extending beyond the aforesaid grips. The extremities of the ends 16 extend beyond the grips so as to facilitate engagement and disengagement and satisfactory retention. The superimposed 35 central portions of the two bars are contained in a sleeve-like attaching member or coupling 18 forming a part of a rectangular frame adaptor element 17. The adaptor element is sufficiently large to project above and below the two bars 40 so that it may be stitched as at 19 to the back of the knot as shown in Figure 2. When in position the features 15 and 16 extend well beyond the knot so as to conveniently grasp the adjacent edges of the folds 8 of the collar as illustrated 45 in Figure 1. Hence, as before indicated, the clasp or clip 14 serves as the sole means for holding the tie in place and obviates the necessity of special attaching hooks and the like connectible with collar buttons.

The essence of the invention, however, is in the combination tie and ornamental clip and adaptor idea wherein the part 14 of the clip serves as an ornamental stay for maintaining the folds 8 of the collar in correct well-balanced and neat wearing relationship.

It is thought that persons skilled in the art to which the invention relates will be able to obtain a clear understanding of the invention after considering the description in connection with the drawing. Therefore, a more lengthy description is regarded as unnecessary.

5 Minor changes in shape, size, and rearrangement of details coming within the field of invention claimed may be resorted to in actual practice, if desired.

10 We claim:

An article of manufacture of the class described

comprising, in combination, a made-up necktie of the four-in-hand type including a knot, aprons, and positioning tabs carried by the knot and adapted for disposition between the neck band and outer folds of a conventional collar, an adaptor element stitched to the back of the knot, an ornamental retaining clip attached to said adaptor element, said clip serving to retain the tie on the collar as well as to hold the outer folds of the collar in symmetrical position.
